WRITING INSTRUMENT

Helmut Karl Bross, 40 Weichselgartenstrasse, Altenberg, über Nurnberg, Germany, assignor of fifty percent to Frank T. Johmann, Berkeley Heights, N.J.

Filed Nov. 20, 1961, Ser. No. 153,374

2 Claims. (Cl. 120—42.1)

This invention relates to writing instruments. Particularly, the invention relates to a writing instrument having a writing point at each end of the instrument.

Writing instruments, e.g. pencils, having a fixed writing point at each end of the instrument are well known. Usually, such double pointed instruments have writing points which write in different colors, frequently red and blue. These instruments are often used by draftsmen, teachers, etc. for both normal writing (e.g. in blue color), and marking errors or corrections (e.g. in red color). Recently, ballpoint pens having different colored, fixed, non-retractable, writing points have become common, and are usually provided with two caps, one for each end of the instrument so that the fixed points can be covered for carrying. One form of the present invention is directed to a simple writing instrument having two writing points, one at each end of the instrument casing, wherein retraction of one point into the instrument casing will automatically project the other point for writing. This form of the invention is preferably used with a single cap carrying a pocket clip, said cap fitting over either end of the instrument. Thus, the cap can be used to cover the projected point of the instrument, and since the other point is retracted into the casing, the instrument can then be readily carried in a pocket, purse, etc. Another form of the present invention permits projection of one point while retracting the other point, and also permits both points to be moved to a retracted position. Since both points can be retracted, there is less need for a cap for carrying purposes and a spring pocket clip can be fastened directly on the instrument casing if desired. Another form of the present invention permits both points to be projected at the same time, while also permitting retraction of one point and projection of the other point. This last form enables the instrument to be safely carried with a single cap covering the exposed point, and at the same time permits both points to be exposed for writing at the same time. This last feature is of value to those users who frequently change back and forth between the two writing points, since with both points exposed, the instrument merely has to be turned in the hand to employ either point.

In all of the above forms, the points of the instrument can be retracted by merely pressing the projected point firmly against a rigid surface, such as a writing surface or a cap. This firm pressing releases a latch and allows the projected point to move toward a retracted position within the instrument casing. Or, a cap can be pushed down against the exposed point to retract said exposed point or to project the retracted point.

The invention will be further understood by reference to the following description and the drawings, which include a preferred embodiment of the invention.

In the drawings:

FIGURE 1 is a longitudinal view, partly in cross-section, of a writing instrument of the invention having its lower point projected and its upper point retracted.

FIGURE 2 is a longitudinal view, partly in cross-section, illustrating how the lower point of the instrument can be retracted and the upper point protracted.

FIGURE 3 is a cross-sectional view taken along the lines 3—3 of FIGURE 1.

FIGURE 4 is a longitudinal view, partly in cross-section, showing how a cap can be used to retract one point

2

and protract the other point of the embodiment of FIGURES 1 to 3.

FIGURE 5 is a fragmentary view, partly in cross-section, illustrating a different latch means.

FIGURE 6 is a fragmentary view, partly in cross-section, illustrating still another latch means.

FIGURE 7 is a cross-sectional view taken along the lines 7—7 of FIGURE 6.

FIGURE 8 is a fragmentary view, partly in section, illustrating yet another latch means.

FIGURE 9 is a longitudinal view, partly in section, of another embodiment of the invention, with one point retracted and the other point projected.

FIGURE 10 is a longitudinal view, partly in section, of the embodiment of FIGURE 9 with both points retracted.

FIGURE 11 is a longitudinal view, partly in section, of still another embodiment of the invention.

Reference is now made to the drawings in detail, with particular reference to the embodiment of FIGURES 1 to 3. The writing instrument has an outer tubular casing or barrel including the lower barrel section 10 and the upper barrel section 10', which sections are joined together by threaded engagement. The outer ends of the respective barrel sections 10 and 10' are each tapered inwardly as at 11 and 11' and terminate in open ends. The bore extending through the tubular casing is reduced in its cross-section proximate both ends of the casing as indicated at 12 and 12' to thereby form annular interior shoulders 13 and 13'. Tubular hood members 14 and 14', have their inner ends formed with the respective annular flanges 15 and 15', while their outer ends normally project through the adjacent open ends of said casing. Cartridge units 16 and 16' include the short terminal feed tubes 17 and 17' respectively, which in turn carry the respective writing balls 18 and 18'. Coil compression springs 19 and 19', are respectively disposed between the flanges 15 and 15' and the rings 20 and 20' fixed, as by frictional engagement, within the barrel members 10 and 10'. The springs 19 and 19' urge the hood members 14 and 14' to their extended position where their flanges 15 and 15' seat atop the respective shoulders 13 and 13'. Joining said cartridges 16 and 16', is a tubular cartridge connector 21 frictionally engaging the outer surface of the inner portions of said cartridges. The connector 21, and cartridges 16 and 16' are longitudinally movable as a single unit. The connector 21 is internally formed with an annular lip 22, which abuts the inner ends of said cartridges. An air vent 23 admits air to the interior of said cartridge units. Extending downwardly from said connector 21, are spring latches 24, each having an enlarged rounded end 25. Annular grooves 26 and 27 are formed in the barrel member 10, said grooves each having a cross-section complementary to the rounded ends 25.

FIGURE 1 shows the lower ballpoint 18 in a projected position for writing, while the upper point 18' is retracted within its adjacent hood 14'. It will be noted that the spring latch ends 25 are seated in the annular groove 26. The flat latch springs 24 tend to spring apart from each other with sufficient force to maintain their ends 25 seated in the groove 26 against normal writing pressure applied to the writing point 18, particularly when the instrument is held at an angle to the writing surface. However, when the instrument is held vertical to a rigid surface 28, as in FIGURE 2, and then pressed down against said surface with greater than normal writing pressure, then first the point 18, and then the hood 14, are forced upwardly into the instrument casing. The spring ends 25 became dislodged from the groove 26 as the cartridge unit 16 moves upwardly, and are shifted into the annular groove 27, while the upper cartridge unit 16', and its

point 18', are now in a projected position. Upon lifting the lower end of the instrument from contact with said surface 28, the hood 14 will return to its normally extending position by its spring 19. The instrument can then be turned upside down so as to write with the point 18' as the springs 24 by means of their ends 25 seating in the groove 27 will now maintain the point 18' projected against normal writing pressure. It will be apparent that if the now projected point 18' and its adjacent hood 14' are forced into the barrel section 10' under substantial pressure, that the instrument can again be returned to its position of FIGURE 1 where point 18 is projected and the spring ends 25 are again in the groove 26.

If desired, the instrument of FIGURES 1 to 3 can be provided with a cap 29 having a pocket clip 30. This cap can be used to cover the projected point for carrying, and can also be used as a pushbutton. For example, the tubular cap 29, having a closed upper end, can be positioned over the upper end of the instrument in the FIGURE 2 position. Then, the cap is pressed down so as to force said cap to slide down upon the tubular barrel member 10' until it assumes the position of FIGURE 4. The inner wall 31 of the closed end of the cap will thereby force the point 18' and hood 15' to a retracted position relative to the barrel section 10', while at the same time projecting point 18. The tubular walls 31 of the cap fit sufficiently snug around the barrel 10' so as to frictionally hold the cap in the position of FIGURE 4 against the light pressure of spring 19' exerted against the hood 15'. The instrument in the position of FIGURE 4 can be retracted by firmly pressing the point 18 down against a rigid surface so as to force the upper point 18' against the inner end wall 31 of said cap 29 to thereby raise the cap 29 relative to the barrel as indicated by the dotted lines denoting the upper end of the cap. The point 18 will then be inside its hood 14, while the point 18', even though out of its hood 15', will still be concealed within the cap 29. The instrument can then be carried or clipped to a pocket, etc.

FIGURE 5 represents a fragmentary view illustrating a modified tubular cartridge connector 32 having annular flanges 33 and 34 which frictionally engage the inner barrel wall 35 with sufficient force to withstand normal writing pressure, but which will be slidingly movable within said barrel upon sufficient retraction pressure being applied to a projected point.

FIGURES 6 and 7 illustrate a tubular cartridge connector 36 formed with spaced annular grooves 37 and 38 for selective engagement with the deformable indentations or detents 39 formed in spring latches 40. The flat spring latches 40 are held in place by the tubular ring 41 frictionally engaging the inner wall of the tubular barrel 42. The indentations 39 flatten out sufficiently to allow movement of the connector 36 upon sufficient longitudinal force being applied to said connector 36.

FIGURE 8 represents another latch system where the cylindrical connector 43 is provided with a bore 44 carrying a spring 45 urging the latch balls 46 outwardly so as to be engageable in the annular grooves 47 and 48 formed in the inner wall of the tubular barrel member 49. The latch balls 46 move inward into the bore 44 upon being displaced from their annular grooves. It will be apparent that any of the latching systems of FIGURES 5, 6 and 7, or 8, can be substituted for the connector 21, spring latch elements 24 and 25, and the grooves 26 and 27 of the embodiments of FIGURES 1 to 4.

The writing instrument of FIGURES 9 and 10 is similar to that of FIGURES 1 to 3 with the primary exception that the lower barrel section 50 is internally formed with three longitudinally spaced annular grooves 51, 52, and 53. The detents, i.e. latch springs ends 54, when engaged in groove 51, holds the lower point 55 in a protracted position. By pressing the point 55 against a rigid surface with greater than normal writing pressure, the

latch ends 54 can be moved up to engagement in the center groove 52 as shown in FIGURE 10. Here, it will be noted that both the point 55 and point 56 are retracted within their adjacent hoods 57 and 58. Thus, the instrument can be carried in this position without a cap. It will be apparent, that by pressing the hood 57 and point 55 into contact with a rigid surface, that the latch ends 54 can be shifted into groove 53 to thereby hold lower point 55 still retracted and upper point 56 projected. Subsequent projection of point 55 can, of course, be achieved by applying pressure to point 56 and hood 58. In this type of instrument having three latch positions, it is preferred to use a spring or snap latch of the type shown which will make a clicking sound when seating in the grooves 51, 52 and 53. In this way, the user can judge from the clicking sound when the ends 54 have seated in the center groove 52. On the other hand, seating of the spring ends 54 in the grooves 51 or 53 will occur automatically by pressing the appropriate end of the instrument into contact against a rigid surface until the contacting hood and adjacent point are pressed into the barrel as far as they can and the rigid end of the barrel contacts said surface.

The embodiments of FIGURE 11 are quite similar to that of FIGURES 9 and 10, except that the cartridge units are slightly longer, so that when the spring latch ends 54' are in the center groove 52', both points 55' and 56' are projected. Movement of said latch ends 54' to engagement within the annular recess 53' will further project point 56', while retracting point 55'. On the other hand, movement of said latch ends 54' into the recess 51' will retract point 56' and further project point 55'.

In sum, the present invention provides a simple, inexpensive, readily operated, double pointed writing instrument having a minimum of parts. It will be apparent that a number of minor variations can be made without departing from the scope of the invention.

I claim:

1. A ballpoint pen comprising: a tubular casing having an upper and a lower end and open only at said ends; upper and lower tubular hoods extending through said ends of said casing and longitudinally movable relative to said casing; springs within said barrel urging said hoods outwardly relative to said casing; a rigid writing assembly having an upper writing point and a lower writing point at a fixed distance from each other, said assembly including a tubular cartridge connecting member and upper and lower ballpoint cartridges carried by said connecting member, said assembly being longitudinally movable within said barrel between (1) a first position wherein said lower writing point extends through the outer end of said lower hood and said upper writing point is concealed within said upper hood and (2) a second position wherein said upper writing point extends through said outer end of said upper hood and said lower writing point is concealed within said lower hood; and latching means defined by said connecting member and said casing to selectively hold said assembly in said first and said second positions against normal writing pressure applied to the extended writing point, but yieldable upon the application of inwardly directed pressure to said extended writing point and the adjacent hood in excess of normal writing pressure; said inwardly directed pressure being obtainable and said assembly being shifted between said positions by pressing said extended writing point and said adjacent hood into contact with a rigid surface to thereby longitudinally move said extended writing point and said adjacent hood inwardly into said casing and then releasing said extended writing point and said adjacent hood from said contact, whereby (a) said adjacent hood returns to its original position, (b) said extended writing point has now been moved to a concealed position within said adjacent hood and (c) said assembly has been

shifted from one of said positions to the other of said positions.

2. A writing instrument according to claim 1, wherein said barrel is formed with lower and upper internal annular recesses and said latching means comprises a spring latch carried by said connecting member and having a detent portion engageable in said recesses, said detent portion when engaged in said lower recess holding said assembly in said first position, said detent portion when engaged in said upper recess holding said assembly in 10 said second position.
